UNITED STATES PATENT OFFICE.

GAËTAN DOBKEVITCH, OF PARIS, FRANCE, ASSIGNOR TO SOCIÉTÉ INTERNATIONALE
DE LA LAMPE ÉLECTRIQUE C. R., OF PARIS, FRANCE.

APPARATUS FOR WINDING THE FILAMENTS OF INCANDESCENT ELECTRIC LAMPS ON THEIR SUPPORTS.

1,039,657.

Specification of Letters Patent. Patented Sept. 24, 1912.

Application filed April 30, 1912. Serial No. 694,231.

To all whom it may concern:

Be it known that I, GAËTAN DOBKEVITCH, a subject of the Russian Empire, residing at 185 Rue du Château des Rentiers, Paris, France, have invented certain new and useful Improvements in Apparatus for Winding the Filaments of Incandescent Electric Lamps on Their Supports, of which the following is a specification.

10 This invention has for its object an apparatus for winding, or mounting on their supports, the filaments of incandescent electric lamps, either in their crude condition as obtained by pressing plastic pastes, or in 15 the metallic condition as obtained by drawing or by the chemical formation of the pressed filaments.

The use of this apparatus is intended more particularly when the filaments must be 20 fixed on their supports at a large number of points, and the portions of the filaments (or chains) comprised between two consecutive fixing points must be of a given length which is greater than the distance separating the 25 two fixing points; the filaments then have a certain slackness.

The apparatus which forms the object of the present invention enables the necessary slackness to be easily given to the filament 30 which is being wound, and the length of the portions of the filament between consecutive points of attachment to be automatically measured with all desirable precision.

35 The apparatus is substantially composed of a central member for fixing the support on which the filament is to be wound, and arms arranged parallelly or obliquely to the support and adapted to be maintained 40 at a given distance from the support during the operation of fixing the filament, and then simultaneously approached to it in order to release the wrapped support. The apparatus may, for instance, comprise in 45 practice a central shaft which is bored axially at one of its ends, and for a portion of its length and provided at this same part with a certain number of longitudinal slots intended to give passage to the arms or 50 hooks of the filament support, the central part of which is inserted in the bore of the shaft and fixed in any suitable way. A series of movable arms are arranged about the central shaft and are held away from

it at a given distance, which may be regulated at will. These arms on which the filament is wrapped or folded during the winding, prevent any displacement of sections of filaments between the consecutive points of attachment on the support, and give them automatically the desired length. These arms are finally arranged so as to be able to be approached to the shaft, and thus to liberate the sections of the filament which may be easily removed ready wound or mounted on its support.

In the case of a filament support which has a central tubular part, the perforated and slotted shaft may be replaced by a simple smooth rod on which the support is fitted, and fixed in any suitable way.

A method of carrying out this invention is shown as an example, in two views in perspective in the accompanying drawings.

The apparatus is substantially composed of a central shaft *a* with an axial bore *b* for a portion of its length at one end, and provided with longitudinal slots *c* over this same part. Four slots corresponding to four rows of support arms are shown in the drawings, but their number may evidently be any suitable one. A ring *d* which has internally the shape of a truncated cone, may be fitted over the split and perforated end of the shaft *a* and enables the support *e* of the filament to be completely fixed after the latter has been inserted in the central bore *b*, while the arms or hooks *f* of the support pass through the slots *c*. At its other end, the shaft *a* fits with slight friction in a sleeve *g* mounted in a support fixed on the worktable in any suitable way. A milled disk or button *h* enables the workman to turn the sleeve *g* at will by hand, and consequently the whole apparatus on itself.

A series of rods or arms *i* are arranged about the central shaft *a*, and, for instance, in planes which bisect angles formed by the planes of the series of arms or hooks *f* of the support when in position. These arms *i* may be arranged either parallelly with the shaft *a* or obliquely relatively thereto, so as to form with it in this latter case a given angle. This latter arrangement must be adopted when the sections of the filament are to be of variable length which increases or decreases progressively between consecutive points of attachment. Jointed arms *j*

or links forming with the arms *i* and the shaft *a* the sides of jointed parallelograms or trapeziums, connect the arms *i* with the central shaft of the apparatus. Finally a tool or link *h* jointed at its two extremities connects each arm *i* to a sleeve *l*, which slides on the shaft *a* but the displacement of which on this shaft is limited by a shoulder *m* of the shaft against which it abuts. The position of this sleeve *l* on the shaft *a* determines the spacing of the arms *i* and their distance from the axis of the apparatus. This separation of the arms may be insured in a constant manner, to the extent which may be desired for obtaining a given length of the sections of the filament, by means of springs *n* which tend to maintain the arms constantly away from the shaft, and by regulating the position of the part *o* of the sleeve which abuts against the shoulder *m* of the shaft. With this object the sleeve *l* is split at *p* for a part of its length, and fits on a socket *o* forming an adjustable abutment, a screw *q* enabling the sleeve to be adjusted on the socket at any given point of the length of the latter.

The arrangement shown in the drawings for fixing the arms *i* insures the perfect rigidity of the whole, and is particularly advantageous when it is desired that the arms shall be capable of being extended to a variable amount. Instead however of fixing the arms *i* to the shaft *a*, by means of jointed parallelograms or trapeziums they might also be connected to the shaft by a single joint, in that case the arms *i* if necessary being given a suitable curvature which would insure, in the winding position, the operative parts of the arms (on which the filament is wound) remaining parallel with the shaft *a*.

The arms *i* may of course have such a formation or peculiarities, recesses, nipples and the like, as are necessitated by the arrangement of the arms of the support, for instance. It is only essential that the arms shall be able to be operated so as to liberate the filament, when the winding is completed, either by approaching the arms toward the axis, or by a movement of rotation of the arms around the axis, and to facilitate its removal.

The apparatus hereinbefore described works as follows: - The apparatus having been fixed in the sleeve *g* and secured by the screw *g'*, the workman fixes the free end of the filament *r* on a suitable arm or hook *f* (for instance the first starting from the bottom of the support) by means of a suitable adhesive or mechanically. He then turns the apparatus by means of the milled button *h* and the filament is bent by being pressed on one of the arms *i* (Fig. 1) and then the workman fixes it to the following arm and so on. When the winding of the filament is

completed the workman approaches the arms *i* to the shaft by compressing the springs *n*, the sleeve *l* sliding on the shaft *a* from the front to the rear; the sections of the filament previously stretched by the arms *i* are then set free and the workman has only to withdraw the support *c* with its filament mounted thereon after having taken care to remove the locking ring *d*.

I declare that what I claim is:—

1. An apparatus for winding and mounting the filaments of incandescent electric lamps on their supports, comprising a central shaft adapted to hold the filament support, means for supporting and rotating said central shaft, a plurality of arms around which the filament is bent during the winding disposed about said central shaft, and movable toward and away from the same, means for connecting said arms to the central shaft in such a manner that they may be held at a given regulatable distance therefrom so as to give to the sections of the filament between two consecutive points of attachment on the arms of the filament support the desired length, and means for simultaneously approaching the said arms toward the central shaft to enable the support with the mounted filament to be removed.

2. An apparatus for winding and mounting the filaments of incandescent electric lamps on their supports, comprising a central shaft for holding the filament support, means for supporting and rotating said central shaft; a plurality of arms disposed about the said central shaft, parallel thereto and movable toward and away from the same, links jointed respectively to the said arms and central shaft, and forming therewith the sides of jointed parallelograms or trapeziums, means tending to hold the movable arms away from the central shaft and spaced apart from each other, and means for simultaneously approaching the said arms toward the central shaft.

3. An apparatus for winding the filaments of incandescent electric lamps on their supports, comprising a central shaft having an axial bore at one end to receive the filament support, longitudinal slots in said shaft for giving passage to the arms or hooks of the filament support, means for securing the said support in the bore of the said shaft, means for supporting and rotating the said central shaft, a plurality of movable arms disposed about the said central shaft and movable toward and away from the same, means for connecting the said arms to the central shaft in such a manner that they may be held at a given regulatable distance therefrom, and means for simultaneously approaching the said arms toward the central shaft.

4. An apparatus for winding the filaments

of incandescent electric lamps on their supports, comprising a central shaft adapted to hold the filament support, means for supporting and rotating said central shaft, a plurality of arms disposed about said central shaft and movable toward and away from the same, links jointed respectively to the arms and central shaft and forming therewith the sides of jointed parallelograms or trapeziums, means tending to hold the movable arms away from the central shaft and spaced apart from each other, and means for simultaneously approaching the said arms toward the central shaft comprising a sleeve adapted to slide on the central shaft and connected by jointed links to the said arms.

5. An apparatus for winding the filaments of incandescent lamps on their supports, comprising a central shaft for holding the filament support, means for supporting and

rotating said central shaft, a plurality of arms disposed about said central shaft and movable toward and away from the same, jointed links connecting the said arms to 25 the central shaft, springs for holding the movable arms away from the central shaft and spaced from each other, a sleeve adapted to slide longitudinally of the central shaft and connected to the movable arms by 30 jointed links, and adjustable means in connection with said sleeve for regulating its movement in one direction on the central shaft.

In witness whereof, I have hereunto 35 signed my name this 15th day of April 1912, in the presence of two subscribing witnesses.

GAËTAN DOBKEVITCH.
